TEXTILE MACHINERY

Edward Kinsella, Spondon, near Derby, England,
assignor to British Celanese Limited, London,
W. I., England, a company of Great Britain

Application May 5, 1944, Serial No. 534,186
In Great Britain April 22, 1943

12 Claims. (Cl. 242—35.5)

This invention relates to textile machinery and particularly to machinery for winding yarn in the form of cylindrical packages in which the package being formed is rotated by the rotation of a spindle carrying it and in which the spindle speed is varied so as to give the package a constant peripheral speed and consequently to provide a constant rate of take-up or collection of the yarn.

Yarn winding apparatus of this kind is particularly suitable for the winding of threads of artificial filaments continuously with their production since it enables the threads, which are produced at a constant linear rate, to be taken up at the same constant speed as that at which they are produced, notwithstanding the fact that during the growth of a package from the empty to the full state its diameter is constantly increasing. U. S. Patent No. 2,266,121 describes a cheese winding machine of this kind in which, moreover, provision is made for changing over on completion of a cheese from a full package to an empty spool so that continuity in the collection of the thread as fast as it is produced is maintained. In the machine described in U. S. Patent No. 2,266,121, constancy of the peripheral speed of the package being wound is maintained by the provision of infinitely-variable speed gears for driving the spindles and a cam for changing the speed ratio of said gears inversely as the expected rate of increase of the package diameter.

It has now been found advantageous in machines of this kind to make the spindle speed depend not merely on the expected rate of growth of the package but on the actual growth of the package so as to eliminate any variation in take-up speed that might arise, e. g. from variations in yarn tensions due to atmospheric conditions, which could not be taken into account in computing the expected rate of growth of the package and the corresponding form of the cam controlling the spindle speed. It is an object of the present invention to provide a cheese winding apparatus in which such further refinement of control is effected. It is a further object of the invention to provide a machine in which the change from a full package to an empty package carrier may be effected not only without interruption in the continuous collection of the thread but also in a fully automatic manner at predetermined intervals.

According to the present invention, a method of winding yarn at a substantially constant linear speed comprises feeding the yarn to a rotating package, driving the package through variable speed means having speed control means associated therewith, driving said speed control means through a slipping drive, and controlling the degree of slip in said slipping drive in accordance with the divergence of the actual rate

of growth of the package from an arbitrary rate of growth preselected to be greater than the actual rate of growth, whereby the peripheral speed of the package is maintained constant notwithstanding the increase of its diameter. Preferably the preselected rate of growth is chosen so as to be only slightly higher than the calculated rate of growth of the package, so that the divergence and consequently the degree of slip

10 are small, though always present.

A yarn winding apparatus for carrying out the method defined above comprises a spindle, infinitely-variable gear means for driving said spindle, control means, such as a cam, adapted on 15 being steadily driven to decrease steadily the speed ratio of said gear means, clutch means for driving said control means, said clutch means having a driven member and a driving member, a feeler for the surface of the package being wound adapted to move one of said members in accordance with the diameter of the package and means for moving the other of said members in accordance with the rate at which said package is being rotated. By these means, as the package 20 grows it acts through the feeler to engage the clutch driving the cam or like means controlling the speed ratio of the gear means, which cam means, besides decreasing the speed of the spindle, disengages the clutch means so as to 25 prevent further decrease in the speed of the spindle until further growth of the package takes place. In the operation of the machine the intervals between successive engagements and disengagements of the clutch in this manner may 30 be made so short (having regard to the fact that the operations of engagement and disengagement are not absolutely instantaneous but occupy a small measure of time) that the resultant effect is equivalent to a steady slipping of the clutch 35 to give the requisite speed to the cam controlling the infinitely-variable speed gear.

The cam will have a maximum speed corresponding to full and constant engagement of the clutch through which it is driven, and accordingly the form of the cam should be such that, if it were always driven at that maximum speed, it would at any time decrease the speed ratio at a greater rate than is called for by the expected rate of increase of the package diameter; this is 45 necessary so that the cam, being actually driven with a mean speed less than this maximum speed, may in fact decrease the speed ratio at a rate corresponding directly to the actual rate of increase of the package diameter. It is desirable 50 however that this divergence of the cam form from that which would be required if the cam were constantly driven should be as small as is consistent with leaving a margin for possible variations of the package diameter from what is 55 expected. In this way the necessary slipping of

the clutch driving the cam is reduced to a minimum.

As the feeler for the control of the first clutch member the traverse guide by means of which the yarn is traversed to and fro along the length of the package being formed may be employed, the traverse guide being arranged to make light contact with the surface of the package and to be pushed away from the axis of the package as the package grows. As the means for controlling the position of the second clutch member there may be employed a further cam mounted on the same shaft as that which controls the infinitely-variable gear. Since the spindle speed at any time depends on the position of the cam controlling the infinitely-variable gear the placing of the second cam on the same shaft creates the required condition that the second clutch member should be controlled in accordance with the spindle speed.

While the invention, being concerned primarily with the control of the spindle speed during the actual winding operation, is applicable to machines in which winding is stopped at the end of each winding operation in order to change from a full package to an empty spool it is particularly advantageous in machines in which, as in U. S. Patent No. 2,266,121, arrangements are provided to collect the yarn continuously and to change spools without interrupting such collection. Indeed it is a further feature of the invention to provide, in continuously operating machines of this kind, automatic means for effecting the change-over at predetermined time intervals.

For this purpose a cam or cam system may be used, driven through a reduction gear from some convenient and constantly operating part of the machine, for putting into action a drive to the change-over mechanism by means of which the substitution of an empty package support for a full package is effected. At the same time the cam or cams controlling the infinitely-variable gear are re-set to the correct position for starting a fresh winding operation. Where, as in U. S. Patent No. 2,266,121, the spindles and their drive including the infinitely-variable speed gear are duplicated, this also involves putting into operation the spindle drive which was idle during the formation of the completed package. The re-setting of the infinitely-variable speed gear may conveniently have been effected in the interval during which the spindles driven by it were idle, e. g. immediately after the completion of a working cycle on the part of that drive.

By way of example a cheese winding apparatus according to the present invention, similar in many respects to that described in U. S. Patent No. 2,266,121 and designed to serve as the winding mechanism of a dry spinning apparatus for the production of threads and artificial filaments will now be described in greater detail in reference to the accompanying drawings in which:

Figure 1 is a front elevation of the winding mechanism as applied to a dry spinning apparatus,

Figure 2 is a plan of part of Figure 1,

Figure 3 is a rear elevation in section through the upper part of the gear box shown in Figure 1,

Figure 4 is a plan of the mechanism shown in Figure 3 taken in section on the line 4-4 of Figure 3 with the cover removed, and some of the underlying mechanism (shown in Figure 5) omitted for greater clarity,

Figure 5 is a plan in section on the line 5-5

of Figure 3, further broken away at certain parts to show additional details,

Figure 6 is a detail of Figure 5,

Figure 7 is a front elevation in section through the right hand end of the gear boxes shown in Figure 1, and

Figure 8 is a detail, partly in section, of the mechanism shown in Figures 5 and 7.

As in U. S. Patent No. 2,266,121, the machine 10 comprises a trunnion casing 11 of substantially rectangular cross-section mounted so as to turn about its longitudinal horizontal axis and having package carrying spindles 12 protruding from to opposite sides of the casing, the spindles 12 being 15 parallel to each other and lying respectively above and below the trunnion axis. Two shafts 13 extending lengthwise of the trunnion casing drive respectively one of each pair of spindles, each of the shafts being driven, as described in the prior 20 patent, through an infinitely-variable gear whose control will be described in greater detail hereafter. The trunnion casing extends along a number of spinning cells 14 and provides a pair of spindles 12 for each thread produced in the cells. The thread 16 is delivered by the feed roller 15 25 of the spinning cells 14, downwardly to one side of the trunnion casing 11 and the spindle 12, for the reception of the carrier support or spool which is to take the thread 16, lies below the trunnion 30 axis and extends towards the spinning cell 14. The trunnion casing 11 is arranged to rotate so as to carry that spindle 12 downwards and below the trunnion axis and so round to a doffing position, at the same time bringing the other spindle 35 12 carrying an empty package support or spool, upwards over the trunnion axis and into the winding position. Alongside the winding position is mounted a traverse box 17 from which extend a series of thread guides 18 each having a 40 stroke appropriate to the length of the cheese, the several guides 18 being driven by cams 19 mounted on shafts 20 driven by a common shaft 21 in the box 17.

The trunnion casing 11 extends from a gear 45 box 25 containing the infinitely-variable gears (generally positioned one behind the other at 26) for driving the shafts 13 and the mechanism for controlling the output speeds of the gear boxes 26 and the change-over from one set of spindles 12 to the other on the completion of a series of 50 cheeses. The main drive to the mechanism enters the gear box at 25 by a sprocket 27 mounted on the main shaft 28. As shown in Figure 7 the main shaft 28 carries a gear 29 which drives two gears 30 (one on each side of the plane of section of Figure 7), each of which is connected by a clutch 31 to the input shaft 32 of one of the infinitely-variable gears. One of the gears 30 also engages a gear 33 which is connected through a 55 train of gears 34 to a sprocket 35 which, through sprockets 36 (Figure 1) and shafts 37, 38 drives the spinning pumps 39 mounted at the top of the spinning cells 14. The other end of the main shaft 28 carries a sprocket 40 which, through 60 chains and intermediate sprockets (not shown) drives the feed roller 15. The main shaft 28 is also connected, through a ribbon-breaking device of the kind described in the prior patent, and disposed generally at 41, to a sprocket 42 connected by a chain to a sprocket 43 mounted on the shaft 21 entering the traverse box 17. The end plate 44 covering the train of gears 34 is removable so that the gears can be changed in order to alter the speed ratio between the spinning pumps 39 on the one hand and the feed 65 70 75 78

roller 15 and spindles 12 on the other hand, in order that yarns of different deniers may be produced if desired.

The means whereby the change-over from a full package to an empty package support is effected by the rotation of the trunnion 11 through an angle of 180° are exactly as described in the prior patent, the remainder of the present description being directed to the manner in which the spindle speed is controlled during winding and the manner in which the rotation of the trunnion 11 as indicated above is timed and effected.

For the purposes of the present invention the traverse guides 18 are arranged so as to press lightly against the package being wound on the spindle 12, being mounted on a frame 45 pivoted on the shaft 20 of the traverse cam 19. The frame 45 is capable of swinging outwards from the package under pressure and is suitably counter-weighted at 46 so that only light pressure is required to bring about this result. Each of the series of traverse guide frames 45 is connected at 47 to a thread guide retractor rod 48 extending the length of the machine, which rod is actuated during the winding operation to move in the direction of its length by the movement of the traverse guides 18 away from the spindle axes 12 as the packages are growing and which, at the end of the winding operation is independently retracted so as to allow the traverse guides 18 to swing away from the surfaces of the completed packages. This is effected from a control mechanism in the gear box 25.

Within the gear box 25, as shown in Figure 3, the trunnion casing is provided with an external worm gear 50 engaging with a worm 51 which may be driven, at timed intervals, through a clutch 52 provided for the purpose, hereinafter called the roll-over clutch. In the drive to the worm 51 there is also included a slipping clutch 53 (Figures 4 and 5) to allow the shaft 54 carrying the worm 51 to be overdriven without applying excessive torque to the worm. The drive to the clutch 52 comes from a sprocket 59, inside the gear box 25 on the same shaft as the sprocket 42, which drives a sprocket 59 (Figures 1 and 5) and, through a pair of skew gears 159 (Figure 5), the clutch 52. The trunnion 11 is held in one or other of two working positions, displaced at 180° with reference to one another, by means of one or other of two locking pins 55 entering holes 56 (Figure 3) provided on the surface 57 of the part of the trunnion casing lying inside the gear box 25. The operative pin 55 engages the corresponding hole 56 in the casing while the inoperative pin 55 presses on the surface 57 of the trunnion casing, both pins being spring loaded at 58.

The two shafts 13 extending the length of the trunnion casing for the purpose of driving the spindles are driven respectively by the two infinitely-variable gear mechanisms 26 (Figures 1 and 5), which are driven from the main input shaft 28 of the machine through the two clutches 31 (Figure 7). The clutches 31 are actuated from opposite ends of a lever 60 centrally pivoted at 61, so that when one clutch 31 is engaged the other is disengaged. The lever 60 is actuated by the locking pins 55 for the trunnion casing 11. Each pin 55 passes through a hole in the lever 60 and through a hole in the lower end of a vertical lever 62 and carries a head 63 acting on the lever 62, and through it on the lever 60. In this way the operative locking pin 55 may be brought out of engagement with its hole 56 in the trun-

nion casing (as is necessary for the rotation of the trunnion casing) without disturbing the lever 60. When, however, the previously inoperative locking pin 55 drops into its hole 56 as the trunnion 11 completes its movement, it acts upon the lever 60 (and incidentally upon the corresponding lever 62) so that the clutch 31 previously engaged is disengaged and vice versa. The engagement of the newly operative clutch 31 is effected immediately on the engagement of the locking pin 55; the disengagement of the previously engaged clutch 31, however, is delayed for a short time for a purpose hereinafter described. This is effected by actuating each clutch 31 through lever 65 (Figure 7), connected to the appropriate end of the lever 60 by means of a spring loaded link 66 which is shown partly in section in Figure 8. The link 66 is capable of being compressed instead of disengaging the clutch 31, a fluid dash pot 67 being provided to oppose the disengagement of each clutch 31 so that the spring loaded link 66 is first compressed on engagement of the locking pin 55 and then slowly disengages the clutch 31 against the resistance of the dash pot 67.

The mechanism described above (reference 50 to 67) is for the purpose of effecting the rotation of the trunnion casing 11 through 180° C., and the transference of the drive from one set of spindles 12 to the other. The mechanism is operated at intervals by means of two cams 70, 71 (Figures 3 and 4) freely mounted on a common shaft 12 and driven from the main drive through a considerable reduction gearing which includes an eccentric, a pawl oscillated by the eccentric and a ratchet wheel slowly driven by the pawl. The drive comes from the main shaft 28 through gear 29, 30, 33 and worm gear 73 (Figure 7) to a shaft 74 carrying an eccentric 75 (Figure 1). The eccentric 75 drives a lever 76 connected by link 77 to a lever 78 carrying a pawl 79 acting on a ratchet wheel 80 on a shaft 81. The shaft 81 carries a worm 82 (Figure 3) engaging a worm wheel 83 connected to the cams 70, 71. This arrangement enables the shaft 81, and consequently the two cams 70 and 71, to be rotated by means of a handle 84 so that, if desired, change-over can be effected at any time, even before the packages are completed.

The cam 70 is a release cam, serving merely to disengage the operative locking pin 55 through the corresponding lever 62 so as to release the trunnion casing 11 and to hold the locking pin out of engagement until the trunnion has started to rotate; after this the cam 70 releases the locking pin which, however, remains disengaged since it is no longer in register with the hole 56 in the trunnion casing but is pressing on the surface 57. The cam 71 is the master cam, which acts at regular intervals sufficient for the completion of a set of packages, and causes the roll-over clutch 52 to be first engaged and then disengaged, the time between these two operations being slightly in excess of that required for the rotation of the trunnion casing 11 through 180°. When the trunnion casing 11 has been rotated through 180° the locking pin 55 which was previously inoperative drops into its hole 56 in the surface 57 of the trunnion casing 11 and prevents further rotation, slipping then taking place at the slipping clutch 53 until the roll-over clutch 52 is disengaged.

As shown in Figure 4 the working periphery of the master cam 71 comprises a slow lift and a sharp drop twice repeated round the cam, each

lift and drop occupying 180° of the cam periphery. The cam is engaged on opposite sides by two detents 86, 87 subtending at the centre of the cam 71 an angle slightly less than 180°, this angle being adjustable by micrometer adjustment 91 controlling the position of the detents on their respective levers. The free ends of the levers 88, 89 are connected to one another by means of a strong tension spring 92, and are also connected through parallel links 93, 94 to opposite ends of a short rocking lever 95. The rocking lever 95 is pivoted at its centre on one end of a bell-crank lever 96 of which the other end 97 operates the roll-over clutch 52. The two slow lifts of the master cam 71 act simultaneously on the two detents 86, 87 throughout the winding of each package, and so force the two levers 88, 89 apart against the action of the strong spring 92 connecting their ends. This, however, merely rocks the rocking lever 95 without effecting the position of its pivot, or the position of the bell-crank lever 96. Since the two detents 86, 87 are separated by an angle of less than 180° while the two sharp drops on the cam 71 are 180° apart, detent 86 is released by the sharp drop before the detent 87 and in consequence one end only of the rocking lever 95 is sharply pulled, which moves the bell-crank lever 96 and engages the roll-over clutch 52. After a short time the second detent 87 is released by the sharp drop in the cam 71, which rocks the other end of the rocking lever 95 and moves the bell-crank lever 96 to its original position, disengaging the roll-over clutch 52. The interval between these two actions is in excess of the period necessary to rotate the trunnion 11 through 180° by means of the worm 51 and the worm gear 50 on the trunnion. A cam groove 99 on the outer surface of the trunnion casing 11 within the gear box acts through a knuckled retractor lever 100 upon the retractor rod 48 previously described so as to withdraw the traverse guides 18 clear of the packages during the above operation. The rod 48 passes through and is secured to the free end of the lever 100, which is free to move independently of its inner end by reason of the knuckle at the pivot of the lever. The lever 88 to be operated first has an extension 98 beyond the point of attachment of the spring 92, for a purpose hereinafter described.

The above description deals with the change-over mechanism whereby one set of spindles 12 carrying full packages are moved away from the traversing position while the other set of spindles, carrying empty package supports, are moved into the traversing position, the infinitely-variable gear 26 driving the first set of spindles 12 being declutched from the main drive 28 through the clutch 31 while that driving the second set of spindles 12 is clutched to the main drive through its clutch 31. It remains to be described how this retractor rod 48, operated by the growth of the packages during the winding operation, controls the spindle speed through the infinitely variable speed gears 26 driving the spindles 12.

The two variable gears 26 are controlled as regards their speed ratio by means of plungers 101 (Figure 5) which are spring loaded and act through toggle mechanisms 102 to vary the speed ratio in a manner known in connection with such devices. The two variable gears 26 are assembled so that their plungers 101 are opposed to one another and can be operated on by a single cam 103, referred to as the speed cam. The speed cam 103 has a dwell, at minimum radius, of 180° dura-

tion and a slow rise occupying the remaining 180°. This slow rise terminates in a sudden drop to the minimum diameter. By this arrangement when one of the plungers 101 is engaged on the slow rise of the cam 103 so that the speed of its gear is being steadily decreased the other of the plungers 101 is acting on the dwell of the cam 103 at minimum radius so that its gear 26 is in the position of maximum speed.

10 The speed cam 103 is secured to the shaft 72, together with cam 104, the clutch control cam, having two slow rises and two sudden drops, one for each package cycle occurring during a full rotation of the cams 103, 104. Both cams are driven from the main drive of the machine 28 through a clutch of which both the driven member 105 and the driving member 106 are moveable and under control. The driven member 105 carries a worm 107 engaging with a worm gear 108 mounted on a shaft 109 (Figure 5) carrying a further worm 110, driving a worm gear 111 keyed to the shaft 72. The driving member 106 is driven from the shaft 112 carrying the sprocket 35 by means of a gear 113 (Figure 7) on the shaft 112 driving an idler gear 115 engaging with a gear 116 integral with the driving member 106. The driven member 105 is under the control of the clutch control cam 104 which, through a clutch control lever 117 engaging with the surface of the cam 104, steadily draws the clutch member 105 away from the other clutch member 106 throughout the winding operation. The driving member 106 is under the control of the retractor rod 48 which is actuated by the growth of the packages during the winding operation. To this end, both clutch members 105, 106 are freely rotatable on a slidable shaft 120, the driven member 105 being free to slide along the length of the shaft 120 while the driving member 106 is constrained to move axially with the shaft 120. The end of the shaft 120 extends out of the gear box 25, and is engaged by a spring loaded lever 121, pivoted on a bracket 122, the other end of the lever 121 being acted on by the retractor rod 48. In this way, the retractor rod 48 acting through the lever 121 and shaft 120 steadily pushes the driving member 106 towards the driven member 105 which is under control of the clutch control cam 104. In this way, as the package grows the driving member 106 is pushed into engagement with the driven member 105, which causes the shaft 72 carrying the two cams 103, 104 to be rotated. The rotation of the speed cam 103 reduces the output speed of the operative variable gear 26 and so reduces the spindle speed. The simultaneous rotation of the clutch control cam 104 however withdraws the driven clutch member 105 from the driving clutch member 106 and so stops the drive to the two cams 103, 104 until further growth of the package takes place. In operation the effect produced is that of a constantly slipping drive through the clutch, whereby the two cams 103, 104 are driven substantially constantly but at a rate that is lower than that at which the driving member 106 of the clutch rotates, and is automatically adjusted in accordance with the actual rate of growth of the package.

70 It has already been stated that the form of the speed cam 103 should be such that, if driven constantly at maximum speed (the speed of the driving member 106 of the clutch) it would decrease the spindle speed at a greater rate than would be called for by the expected rate of growth of the package. Most conveniently the form of

the cam can be based on the assumption that it will have a constant speed slightly less than this maximum, regard being had to the mode of variation of the speed ratio with variation of position of the controlling plungers 101 and the expected rate of growth of the package as calculated from the denier of the yarn, the desired linear speed of winding, and the mean density of yarn on the package known by experience to give a stable package. If this is done the form of the clutch control cam 104 should be based on the same assumption as to its speed and should be such that at any time the expected size of the package and the expected position of the cam 104 would bring the two clutch members just into contact. If, then, the package tends to grow faster than is expected the clutch members 105, 106 will be pressed together rather more firmly, giving both cams a speed slightly greater than the assumed speed and diminishing the spindle speed at a greater rate to compensate for the unexpectedly high rate of growth of the package and to give the constant and desired peripheral speed and take-up speed. On the other hand, if the package tends to grow more slowly than was expected the clutch members 105, 106 will be pressed less firmly together, again resulting in the desired peripheral speed and rate of take-up. To express the matter differently, the package diameter determines the position of one clutch member 106 through the retractor rod 48 while the spindle speed determines the position of the other clutch member 105 through the plungers 101, speed cam 103, and the clutch control cam 104. If these two determining factors are so related as to give the desired peripheral speed the clutch members 105, 106 will be engaged with sufficient force to maintain this condition but if not then the clutch members will be engaged either more firmly or less firmly so as to create or restore this condition.

While it is most convenient to base the form of the two cams 103, 104 on assumptions as to the expected rate of growth of the package and an assumed constant speed for the cams, neither of these assumptions is essential. Indeed either cam may have an arbitrarily determined form provided that it is roughly of the shape outlined above, i. e. a gentle rise and a sudden drop. The form of the other cam is then absolutely determined by that of the arbitrarily determined cam, being such that for any package diameter and corresponding position of the driving clutch member, the two cams together bring the driven clutch member into engagement with the driving clutch member if and only if the spindle speed is that required to give the desired peripheral speed. These conditions for the form of the two cams, however, are subject to the proviso that the speed at which they must rotate during the building of an actual package in order to maintain the clutch members in contact must not ever be greater than the maximum speed as determined by the speed of the driving clutch member 106. The preferred method of determining the form of the cams is not only simple in itself but also takes account of this proviso.

At the end of each package cycle, it is necessary to re-set the speed cam 103 and the clutch control cam 104 in preparation for the next cycle. This is done by means of a second or resetting drive through a worm gear 125 (Figures 3 and 5) to the shaft 72 carrying the two cams. The gear 125 and also the gear 111 previously mentioned are connected to the shaft 72 through free-wheel

gear 126, 127 respectively so that when the re-setting drive through gear 125 is in operation this drive, being the faster, overdrives the cam shaft 72 without being hindered by the normal drive thereto through the gear 111. The re-setting drive is connected, as shown in Figure 5 to the main drive of the machine through two clutches 128, 129, the clutch 128 being merely a slipping clutch while the other, the re-setting clutch 129 is capable of engagement and disengagement. The re-setting clutch 129 is actuated by a lever 130 to one point 131 of which is pivoted a rocking lever 132 whose two ends are separately controlled and which lies generally parallel to the lever 130 on which it is mounted. One end of the rocking lever is connected by a link 133 to the lever 117 acted on by the clutch control cam 104. The other end of the rocking lever is connected by a spring link 134 and levers 135, 136 to the extension 98, previously mentioned, of the lever 88 engaged by the master cam 71. It will be recalled that the lever 88 moves sharply to initiate the change-over at the end of the cycle. This sharp movement brings the re-setting clutch 129 into engagement through the rocking lever 132 and the lever 130 controlling said clutch. It is only able to do this, however, if the clutch control lever 117 is in the extreme lifted position, this lever being connected to the other end of the rocking lever 132. This state of affairs is brought about independently of the position of the clutch control cam 104 (which may not yet have lifted the lever 117 to the full extent) by the movement of the retractor lever 100 under the action of the cam groove 99 round the trunnion casing 11. The cam groove 99 moves the retractor lever 100 suddenly in the same direction as that at which it was being moved steadily by the growth of the package, and so brings the driving clutch member 106 controlled by the retractor rod 48 into firm engagement with the driven member 105 thereby displacing the driven clutch member 105 and in consequence the clutch control lever 117 connected to the driven clutch member. The clutch control lever 117 is then pushed to its extreme position irrespective of the position of the clutch control cam 104. In order to retain the lever 117 in the extreme position an automatic latch is provided, as shown in Figure 6, in the form of a spring loaded hook 140 pivotally carried by the clutch control lever 117 and adapted to engage with a stationary pin 141. The actual engagement of the clutch control cam 104 with the clutch control lever 117 is effected through an auxiliary lever 142 pivoted at 143 upon the main part of the clutch control lever 117 and normally held back substantially parallel to it by the engagement of the cam 104, a pin 144 being provided on the main part of the lever 117 against which the auxiliary lever 142 presses in these circumstances. The end of the auxiliary lever 142 also engages with a projection 145 on the base of the spring loaded hook 140, so holding said hook clear of the stationary pin 141 with which it is intended to engage. When, however, the main part of the lever 117 is displaced to its extreme position otherwise than by the action of the cam 104, the spring loaded hook 140 acts to press the auxiliary lever into continued engagement with the cam 104 and out of engagement with the stop pin 144 on the main part of the lever 117. This also enables the spring loaded hook 140 to perform its function of holding the clutch control lever 117 in its extreme position.

When the re-setting clutch 129 is thus engaged,

it drives the gear 125 being itself driven by gear 141 (Figure 5) from shaft 112. In this way both cams 103, 104 are rapidly driven round until a stop 150 projecting from the face of the clutch control cam 104 engages a stop 151 on the auxiliary lever 142. At this stage the auxiliary lever 142 actuated by the working edge of the cam 104, has again released the spring loaded hook 140 from its pin 141 and has moreover reached the drop of the clutch control cam 104 so that both the main lever 117 and the auxiliary lever 142 return to their inward position, while the stop 151 carried by the auxiliary lever is moved out of the path of the stop 150 on the clutch control cam 104 preparatory to the next cycle. At the same time the speed cam 103 is moved round so that the operative plunger 101 passes the sudden drop of the cam and allows the mechanism of the variable gear 26 to return to the position of maximum output speed. In order that the mechanism should return to this position it is necessary that the variable gear 26 should continue to be driven for a short period, and it is for this purpose that the delay in the disengagement of the clutch 31 connecting the infinitely-variable gear 26 to the main drive 28 is provided for as mentioned above by means of the fluid dash pots 67.

The operation of the apparatus as a whole may be briefly recapitulated as follows:

Assuming that the packages being wound have been completed and that changeover is about to take place, the release cam 70 withdraws the operative locking pin from the trunnion casing and, while the pin is still withdrawn, the master cam 71 causes the engagement of the roll-over clutch. The trunnion is thereby rotated through 180°, in the course of which the cam groove 99 acts through the lever 100 so as to retract the thread guides and leave the spindles free to rotate about the trunnion axis. The retraction of the thread guides also engages the re-setting clutch 128 and re-sets the speed cam 103 and the clutch control cam 104 in readiness for the winding of the next group of packages.

As the rotation of the trunnion is completed the guides are returned to winding position and the previously disengaged locking pin drops into engagement with the trunnion in its new position. The engagement of the locking pin clutches in the drive to the new spindles and compresses the link 68 for the de-clutching of the drive to the old spindles. The de-clutching is delayed, however, by the provision of the dash pots 67 so as to allow the infinitely-variable gear drive to the old spindles to be re-set to maximum speed in preparation for the next set of packages to be wound thereby.

During the winding of the packages, the growth of the packages tends to engage the clutch 105, 106 so as to rotate the speed cam 103 and reduce the spindle speed to compensate for the increase in diameter of the packages. The rotation of the speed cam, however, involves also the rotation of the clutch control cam, which tends to disengage the clutch 105, 106 and prevent the spindle speed from being reduced too rapidly. In this way a just compensation of the growth of the package is ensured throughout the winding thereof. When the packages are completed the cycle begins again, the packages previously completed having been removed in the meantime and replaced by empty tubes in preparation for the next cycle.

Having described my invention, what I desire to secure by Letters Patent is:

1. Method of winding yarns at substantially constant linear speed comprising feeding the yarn to a rotating package, driving said package through variable speed means having speed control means associated therewith, driving said speed control means through a slipping drive which, if constantly gripping, would reduce the speed of the package excessively, and moving the two contacting elements of said slipping drive axially during said winding, the leading member in such motion being moved in accordance with the reduction of the package speed and the member following being moved in accordance with the package diameter in such a way that the latter overtakes the former whenever the product of said speed and diameter exceeds a desired constant value and the former escapes from the latter whenever said product falls short of said value, whereby the peripheral speed of the package is maintained constant notwithstanding the increase of its diameter.

2. Method of winding yarns at substantially constant linear speed comprising feeding the yarn to a rotating package, driving said package through variable speed means having speed control means associated therewith, driving said speed control means through a slipping drive which, if constantly gripping, would reduce the speed of the package at a rate slightly in excess of that required to give the desired constant linear speed of winding, and moving the two contacting elements of said slipping drive axially during said winding, the leading member in such motion being moved in accordance with the reduction of the package speed and the member following being moved in accordance with the package diameter in such a way that the latter overtakes the former whenever the product of said speed and diameter exceeds a desired constant value and the former escapes from the latter whenever said product falls short of said value, whereby the peripheral speed of the package is maintained constant notwithstanding the increase of its diameter.

3. Yarn winding apparatus comprising a spindle, infinitely-variable gear means for driving said spindle, control means for said gear means adapted on being steadily driven to decrease steadily the speed ratio of said gear means, clutch means for driving said control means, said clutch means having a driving member and a driven member, a feeler for the surface of the package being wound adapted to move one of said members in accordance with the diameter of the package, and means for moving the other of said members in accordance with the rate at which said package is being rotated.

4. Yarn winding apparatus comprising a spindle, infinitely-variable gear means for driving said spindle, control means for said gear means adapted on being steadily driven to decrease steadily the speed ratio of said gear means, clutch means for driving said control means, said clutch means having a driving member and a driven member, a guide for leading the yarn to the winding spindle, said guide being adapted to engage the surface of the package and being connected to one of said members so as to move it in accordance with the diameter of the package, and means for moving the other of said members in accordance with the rate at which said package is being rotated.

5. Yarn winding apparatus comprising a spindle, infinitely-variable gear means for driving said spindle, a cam for controlling said gear

means adapted on being steadily driven to decrease steadily the speed ratio of said gear means, clutch means for driving said cam, said clutch means having a driving member and a driven member, a feeler for the surface of the package being wound adapted to move one of said members in accordance with the diameter of the package, and, secured to said cam, a further cam for moving the other of said members, whereby said member is moved in accordance with the rate at which said package is being rotated.

6. Yarn winding apparatus comprising a spindle, infinitely-variable gear means for driving said spindle, a cam for controlling said gear means adapted on being steadily driven to decrease steadily the speed ratio of said gear means, clutch means for driving said cam, said clutch means having a driving member and a driven member, a guide for leading the yarn to the winding spindle, said guide being adapted to engage the surface of the package and being connected to one of said members so as to move it in accordance with the diameter of the package, and, secured to said cam, a further cam for moving the other of said members, whereby said member is moved in accordance with the rate at which said package is being rotated.

7. Yarn winding apparatus comprising a pair of spindles, infinitely-variable gear means for driving said spindles, change-over means for bringing each of said spindles in turn into a winding position as to the package wound on the other spindle is completed, control means for said gear means adapted on being steadily driven to decrease steadily the speed ratio of said gear means, clutch means for driving said control means, said clutch means having a driving member and a driven member, a feeler for the surface of the package being wound adapted to move one of said members in accordance with the diameter of the package, and means for moving the other of said members in accordance with the rate at which said package is being rotated.

8. Yarn winding apparatus comprising a pair of spindles, infinitely-variable gear means for driving said spindles, change-over means for bringing each of said spindles in turn into a winding position as the package wound on the other spindle is completed, control means for said gear means adapted on being steadily driven to decrease steadily the speed ratio of said gear means, means in association with said change-over means for resetting said control means, clutch means for driving said control means, said clutch means having a driving member and a driven member, a feeler for the surface of the package being wound adapted to move one of said members in accordance with the diameter of the package, and means for moving the other of said members in accordance with the rate at which said packing is being rotated.

9. Yarn winding apparatus comprising a pair of spindles, infinitely-variable gear means for driving said spindles, change-over means for bringing each of said spindles in turn into a winding position as the package wound on the other spindle is completed, a cam for controlling said gear means and adapted on being steadily driven to decrease steadily the speed ratio of said gear means, means in association with said change-over means for resetting said cam, clutch means for driving said cam, said clutch means having a driving member and a driven member, a guide for leading the yarn to the winding spindle, said guide being adapted to engage the surface

of the package and being connected to one of said members so as to move it in accordance with the diameter of the package, and, secured to said cam, a further cam for moving the other of said members whereby said member is moved in accordance with the rate at which said package is being rotated.

10. Yarn winding apparatus comprising a pair of spindles, infinitely-variable gear means for driving said spindles, change-over means for bringing each of said spindles in turn into a winding position, a time cam for actuating said change-over means, driving means adapted to rotate said time cam through one cycle in the period required for winding a complete package, control means for said gear means adapted on being steadily driven to decrease steadily the speed ratio of said gear means, clutch means for driving said control means, said clutch means having a driving member and a driven member, a feeler for the surface of the package being wound adapted to move one of said members in accordance with the diameter of the package, and means for moving the other of said members in accordance with the rate at which said package is being rotated.

11. Yarn winding apparatus comprising a pair of spindles, infinitely-variable gear means for driving said spindles, change-over means for bringing each of said spindles in turn into a winding position, a time cam for actuating said change-over means, driving means adapted to rotate said time cam through one cycle in the period required for winding a complete package, and means for over-driving said time cam independently of said driving means to facilitate rapid resetting of the apparatus, control means for said gear means adapted on being steadily driven to decrease steadily the speed ratio of said gear means, clutch means for driving said control means, said clutch means having a driving member and a driven member, a feeler for the surface of the package being wound adapted to move one of said members in accordance with the diameter of the package, and means for moving the other of said members in accordance with the rate at which said package is being rotated.

12. Yarn winding apparatus comprising a pair of spindles, infinitely-variable gear means for driving said spindles, change-over means for bringing each of said spindles in turn into a winding position, a time cam for actuating said change-over means, driving means adapted to rotate said time cam through one cycle in the period required for winding a complete package, and means for over-driving said time cam independently of said driving means to facilitate rapid resetting of the apparatus, a cam for controlling said gear means and adapted on being steadily driven to decrease steadily the speed ratio of said gear means, means in association with said change-over means for resetting said cam, clutch means for driving said cam, said clutch means having a driving member and a driven member, a guide for leading the yarn to the winding spindle, said guide being adapted to engage the surface of the package and being connected to one of said members so as to move it in accordance with the diameter of the package, and, secured to said cam, a further cam for moving the other of said members whereby said member is moved in accordance with the rate at which said package is being rotated.

EDWARD KINSELLA.
